COMBINED BRASSIÈRE AND SLIP CONSTRUCTION

Viola Wiley, Los Angeles, Calif.

Application August 30, 1947, Serial No. 771,530

1 Claim. (Cl. 2—73)

1

This invention relates to improvements in undergarment construction and is particularly directed to the combination of a strapless brassière, a strapless slip, and a pair of separate shoulder straps, this arrangement permitting proper and accurate adjustment of the brassière and adequate support for the slip without the use of multiple straps over the shoulders of the wearer.

Various feminine undergarments, such as brassières, slips, foundation garments, corselets and the like, are generally provided with shoulder straps firmly attached to the upper marginal edges of the garments. These straps are also often provided with buckles by means of which the length of the strap may be varied, folds in the strap being held by the buckle, thereby shortening the total effective length of the strap. Since most women wear at least two of these garments, each shoulder is traversed by at least two straps. These straps do not normally occupy an overlapping relation; a brassière strap is usually tighter, supports more weight and is relatively immovable on the shoulder. The strap of a slip, on the other hand, does not support any appreciable amount of weight, and the garment desired is not of a clinging character, and as a result, the straps of a slip generally become easily displaced and require frequent adjustments. This is not only troublesome to the wearer but, under thin, diaphanous upper and outer garments, the plurality of straps traversing the shoulders is deemed to be unattractive.

Straps, normally attached to slips, are provided with adjusting means, such as buckles or the like, but in adjusting such means while the slip is upon the wearer, the shoulders are moved and accurate adjustment is difficult. Since slips are light-weight garments and slip straps are not under tension, such slip straps are readily displaced.

The present invention is directed to undergarment construction wherein the brassière is strapless and the slip is strapless. Both of these garments, however, are selectively attachable to a pair of shoulder strap elements provided with connecting means in longitudinally spaced relation, such connecting means being selectively co-operable with attachment means carried by the top edge margins of the brassière and slip. As a result, both the brassière and the slip are supported by and attached to the pair of separate shoulder straps and accurate positioning of the garments on the body of the wearer may be easily attained.

2

It is an object of the present invention, therefore, to disclose and provide improvements in undergarment construction whereby two or more undergarments may be adjustably held by a single pair of shoulder straps.

Another object of the invention is to disclose, as an article of commerce, a feminine undergarment adapted for encircling the torso and covering the bust of the wearer, said undergarment being free from straps and being provided with attachment means adjacent the top edge margins in the front and rear portions thereof.

A still further object of the invention is to disclose and provide a strapless slip arranged for co-operation with a brassière strap provided with a plurality of connecting means so that the length of the slip and its position on the body of the wearer may be easily adjusted.

These and other objects and advantages of the construction embraced by this invention will become apparent to those skilled in the art from the following description of certain exemplary forms embodying the present invention. In order to facilitate understanding, reference will be had to the following drawings in which

Fig. 1 is an elevation illustrating a brassière and slip, made in accordance with the present invention in position upon the body of the wearer.

Fig. 2 is a perspective view of a brassière made in accordance with the present invention, dashed lines indicating the general location of the separate strap elements in the approximate position assumed upon the body of the wearer.

Fig. 3 is an enlarged view of one of the strap elements.

Fig. 4 is an enlarged vertical section taken through the bust pocket of a brassière showing the combination and mode of attachment between the brassière, slip and separate strap, said section being taken approximately along plane IV—IV of Fig. 1.

The term "brassière" is used herein in a generic sense and relates to any garment capable of encircling the torso and provided with breast-receiving pockets; the invention is not limited to any particular size, style or shape of brassière. The term "strapless brassière," as used herein, refers to a brassière which is not provided with a firmly and irremovably connected shoulder strap or straps. The term "slip," as used herein, refers to a tubular underskirt or tubular garment provided with a front portion or portions extending over the bust. Some slips are provided with upwardly pointed sections both in front and in the rear of the garment; other slips have a substantially

horizontal upper rear margin, whereas, others may even have a centrally depressed margin materially lower, when upon the body, than the front upper edge. The term "strapless slip," as used herein, refers to a slip which does not carry irremovably attached shoulder straps.

As previously stated, the general combination embraced by this invention comprises a strapless brassière, a strapless slip and a pair of separate shoulder straps. Each of the shoulder straps is preferably made of a flexible, limp, compliant material, of ribbon-like character, and of a length adapted to traverse the shoulder of a wearer and extend below the front and rear top edge margins of the brassière and slip. One such strap is illustrated in Fig. 3 wherein the strap 10 is shown in extended form. The strap 10 carries a plurality of connecting means in longitudinally spaced relation near each end of the strap. Although such connecting means may assume various forms, Fig. 3 shows such connecting means in the form of eyelets extending through the strap and longitudinally spaced therealong. Such eyelets are indicated at 12, 13, 14, 15 and 16 at one end of the strap. It has been found desirable to space these eyelets a distance of from one-half ($\frac{1}{2}$) in. to as much as one and one-half ($1\frac{1}{2}$) in. from each other. The eyelets adjacent the extreme end of the strap, such as eyelets 12 and 13, are preferably closer together than the eyelets in the remaining portion of such group, such as, for example, the eyelets 14, 15 and 16. The opposite end of the strap is provided with similar eyelets, such as 17, 18 and 19. The number of such connecting means arranged at each end of the strap 10 may vary.

A strapless brassière is generally indicated in Fig. 2, and it will be seen that it includes the body encircling band 20, the front breast-receiving cups 21 and 22 and a rear closure or connection 23. This strapless brassière is provided with attachment means adjacent the top edge margin in the front and rear portions of the brassière. Such attachment means may comprise small hooks 24 and 25 attached to the upper edges or points of the breast-receiving cups 21 and 22. The band 20 may also be provided with hooks 26 and 27 carried by or attached to the upper edge of such band in the rear of the garment.

When the brassière of Fig. 2 is placed upon the body of the wearer, two separate straps, one of which has been illustrated in Fig. 3, are employed, one of the straps traversing each of the shoulders, the hook elements 24, 25, 26 and 27 co-operatively engaging a desired connecting means carried by the straps. For example, as shown in Fig. 1, the straps 10 and 11 are shown connected to the brassière by the co-operative engagement of the attaching means with the connecting means of the straps. As a result, the wearer may adjust the position of the brassière upon her body with great facility without the necessity of using the troublesome buckles or other means of lengthening or shortening the straps 10 and 11. The portion of the straps which traverses the shoulders of the wearer is smooth and free from impedimenta.

The strapless slip 30 is also provided with at-

5 tachment means carried by its upper edge portions and such means may also comprise hooks as best shown in Fig. 4. The hooks, such as the hook 31, may be engaged with a suitable connecting means or eyelet of the strap 10, thereby causing the slip to adequately or desirably cover the brassière and be adjusted for length in accordance with the desires of the wearer the length of her outer garments, etc. The single strap 10, therefore, supports and is removably connected to both the brassière and the slip.

10 Since many slips are provided with an upper portion made of lace or other easily deformed or structurally weak material, the attachment means, such as the hook 31, may be connected to the upper end of a narrow ribbon, such upper end of the ribbon, as well as the hook 31, being then stitched and attached to the upper marginal edge of the slip. The lower end of such ribbon 33 may then be connected to an intermediate or lower portion of the slip and to the stronger, more continuous material from which the main portion of the slip is made. In this manner, the lacy upper part of the slip is not subjected to the strain, the 15 weight of the garment being transmitted by the ribbon members to the attachment means.

20 It is contemplated that the separate strap elements, together with an associated connecting means, constitute an article of commerce and may be dispensed or sold as a part of a kit including a plurality of hook-like members or other attachment means arranged for co-operation with the connecting means carried by the straps. It is to be understood that instead of eyelets and hooks 25 the connecting means and attachment means may comprise snaps or other fasteners.

I claim:

20 In undergarment construction: a pair of unconnected shoulder straps, each of a length adapted to traverse the shoulders of the wearer and extend below the front and rear top edge margins of a brassière and slip, each of said straps being provided with a plurality of longitudinally spaced eyelets near each end of a strap; a strapless brassière provided with a pair of horizontally spaced hook means adjacent the top edge in the front and rear portions of the brassière; and a strapless slip provided with a pair of hook means adjacent the top edge margin in both front and rear portions thereof, said hook means being engageable with desired eyelets on said straps to position said brassière and slip on the body of the wearer and with respect to each other.
